Albert Radtke

UNITED STATES PATENT OFFICE

ALBERT RADTKE, OF ERKENSCHWICK, NEAR RECKLINGHAUSEN, GERMANY

INSTRUMENT FOR WRITING CHARACTERS ON ADVERTISING BOARDS

Application filed September 20, 1927, Serial No. 220,724, and in Germany September 22, 1926.

When writing the inscriptions on advertising boards, for instance placards for shop-windows, the contours of the characters, and eventually the lines for the light and shade or for cut-out portions, which are parallel to the contours are first drawn with black chalk, whereupon the portions of the surface between these contour-lines are painted by means of a brush. The tracing of the contours requires much time.

This invention relates to an instrument by means of which all the lines for the characters can be traced at the same time. The instrument consists of a plate with a handle and on which several, for instance four holders are fixed side by side, which are designed to hold pencils and are all movable in opposition to springs in longitudinal direction so that, even if the pencils should not wear uniformly, all the pencil-points will be adjusted so as to be in contact with the surface being written upon. The holders are further oscillatable and adapted to be secured in any adjusted position on the plate and removably fixed so that they can be interchanged.

A form of construction of the writing instrument is shown, by way of example, in the accompanying drawing.

Fig. 1 shows an elevation of the instrument.

Fig. 2 is a rear view of Fig. 1, the leads being inserted and one of the holders being shown in section.

Fig. 3 is a side-elevation.

Figs. 4 to 6 show several characters written with the instrument and designed to illustrate the writing.

On a plate *b* having a handle *a* four sleeves *c, d, e, f* are pivotally fixed side by side by means of screws *g*. To secure the sleeves in position clamping screws *h*, which traverse curved longitudinal slots *i* of plate *b*, are provided and in each sleeve a pencil-holder *k* is telescoped. A spiral spring *m* in the sleeve bears against the top-end of the telescoped holder *k*. A tappet *n* projecting through a longitudinal slot *o* of the sleeve limits the shifting movement of the telescoped holder *k*. Each telescoped holder *k*

ends in a slit-sleeve *s* on which sits a clamping ring *r*.

The operation is easy to understand. The pencil holders are adjusted to the desired positions and the instrument is used in a similar manner as a pen for writing ronde.

Fig. 4 shows a traced character.

Fig. 5 the same character finished.

When only three lines are to be traced, as for instance for writing the characters shown in Fig. 6, it is necessary to remove either one of the pencils *p* from the corresponding holder *k* from the corresponding sleeve or one of the sleeves *c, d, e* or *f* from the head.

I claim:—

1. An instrument for writing characters on advertising boards, placards and the like, comprising in combination an elongated plate having a plurality of curved slots extending longitudinally thereof, a handle on said plate, a plurality of sleeves and means for oscillatably mounting them on said plate, clamping screws one for each sleeve and traversing said curved slots of said plate, a pencil-holder in each of said sleeves adjustable longitudinally thereof, and a spring in each sleeve acting upon said pencil-holders.

2. In an instrument as specified in claim 1, said sleeves being arranged side by side in the same plane and adjustably and removably mounted on said plate and each having a longitudinal slot near its lower end, said pencil-holders having a longitudinal slit therein and one being telescoped in each sleeve, a tappet near the top end of each slit holder and engaging with the longitudinal slot of the corresponding sleeve, a ring on said slit holder, and a pencil in the slit portion of each telescoped part.

In testimony whereof I affix my signature.

ALBERT RADTKE.
